FLAT KNITTING MACHINE

Paul Lieberknecht, Einsiedel, near Chemnitz,
GermanyApplication September 10, 1934, Serial No. 743,438
In Germany May 2, 1934

2 Claims. (Cl. 66—109)

My invention relates to flat knitting machines, and more particularly to improvements in the knocking-over combs of such machines.

Such improvements relate to machines in which a fresh piece of fabric shall be knitted to an existing piece along a line positioned intermediate the two edges the existing piece. This is effected by knitting the first course of the new fabric to the selected course of the existing fabric, for instance, to a course at its centre. The existing fabric is placed on the frame needles of the knitting machine with the selected course by means of a transfer bar, so that its two ends hang down from the needles in the shape of the letter V (inverted) in front and at the rear of the selected course. The transfer bar is then removed, the first course of the new fabric is sunk and divided, the knocking-over comb is moved into inactive position, that portion of the existing fabric which hangs down at the rear of the selected course, is folded over so that both portions together hang down in front, the knocking-over comb is returned into active position, and the new fabric is finished by knitting its courses in the usual manner.

This procedure involves certain difficulties in flat knitting machines as designed heretofore because the rear portion of the existing fabric hung on the frame needles is not easily disposed of in such manner that damage to the frame needles and seizing of the sinkers are avoided, and the folding-over of the fabric onto the backs of the frame needles causes loss of time and may lead to damage to the needles.

It is an object of my invention to eliminate the aforesaid drawbacks.

To this end, I so mount the knocking-over comb that it is displaceable with respect to the sinker bar, for instance, by attaching it to a rocker, or a set of rockers, which is fulcrumed on a fixed part of the machine, and I provide means, such as a spring, for pulling the knocking-over comb toward the sinker bar, in combination with means such as a lug on one of the rockers, or on each rocker, for limiting the movement of the knocking-over comb toward the sinker bar.

By these means, and independently of any other movements the knocking-over comb performs in the usual way, it is adapted to be displaced in forward direction into inactive position for all positions of the needle bar, together with but independently of, the needle bar, and in the active position of the knocking-over comb so much clearance is provided between the needle bar, the sinker bar, and the fixed part to which the sinker

bar is secured, on the one hand, and the knocking-over comb and its rocker, or rockers, on the other hand; that the rear portion of the fabric hanging on the frame needles and facing the sinker bar, is not seized or otherwise interfered with, and a pulling device can be attached to this portion.

In the drawing affixed to this specification and forming part thereof a knocking-over comb embodying my invention, and its accessories, are illustrated diagrammatically by way of example.

In the drawing:

Fig. 1 is a partly sectional elevation showing the knocking-over comb in its inactive position, and

Fig. 2 is a similar elevation showing the knocking-over comb in its active position.

Referring now to the drawing, 1 is a part of the machine frame, for instance, its head bar, 2 is the sinker bar, and 3, 4 are the jack and dividing sinkers in the bar. 5 is the needle bar, with the frame needles 6. A bracket 13 is secured to the lower side of the needle bar 5 by screws 14, and a link 15 is pivotally connected to the bracket 13 at 16 for moving the needle bar 5 in the usual manner.

The knocking-over comb 17 is arranged between the sinker bar 2 and the needle bar 5, and is attached to the upper ends of rockers 18 which are fulcrumed at 19 in brackets 20 secured to the base of the head bar 1 by screws 21. One of the rockers 18—or all the rockers—is equipped with a lug 22 adapted to bear against the vertical flange of the head bar 1 for limiting the movement of the rocker, or rockers, toward the sinker bar 2. A spring 23 tends to pull the rocker toward the head bar 1 but is prevented by a stronger spring 24 which is attached to the rocker 18 at one end while its other end is attached to a locking lever 25 fulcrumed at 26. A pawl 27 is pivoted on the locking lever at 28 and, in the position illustrated in Fig. 1, engages behind a check 29 on the frame of the machine. The pull of the stronger spring 24 overcomes the pull of the weaker spring 23 and the rocker or rockers 18 are held away from the bar 1 with its lug 22.

When the pawl 27 is thrown out, as shown in Fig. 2, the spring 24 loses its tension and the spring 23 now pulls the rocker 18 to the left until its lug 22 is arrested by the vertical flange of the head bar 1.

The operation of the machine is as follows: The fabric 30a, 30b to whose selected, in the present instance, central, course 30c the new fabric is to be connected, is transferred to the frame

- needles 6 in the active position of the needle bar 5 and the knocking-over comb 17. When the fabric is on the frame needles 6 with its selected course 30c, the operation of knitting the courses 5 which make up the new fabric, is begun from the selected course 30c. The pawl 21 is thrown out and the spring 23 now pulls the rocker, or rockers, 18 toward the head bar 1 until the lug 22 bears against the vertical flange of the bar, as shown in Fig. 2. It will appear from this figure that the knocking-over comb 17 and the rocker, or rockers, 18 are arrested by the lug 22 at such a distance from the sinker bar 2 and the vertical flange of the head bar 1, that there is 10 ample clearance between these parts, so that not only the rear portion 30b of the fabric is not interfered with but that also a pulling device (not shown) may be connected to the rear portion. 15
- 20 After the first course is knitted to the course 30c and before the needle bar 5 is elevated into sinking position, the knocking-over comb 17 together with the needle bar 5 again is moved forward. In this position the rear portion 30b 25 is moved in forward direction, and thereupon the needle bar 5 and the knocking-over comb 17 are returned together into operative position and the needle bar 5 is lifted into the sinking position, whereupon the further knitting of the fabric portion from one row of loops to the other takes place.
- It is understood that the knocking-over comb 19 may be operated in the manner described, without displacing the needle bar, and I wish it to 30 35 be understood that I do not desire to be limited to

the exact details of construction shown and described for obvious modifications will occur to a person skilled in the art.

I claim:

1. In a flat knitting machine, a sinker bar, a 5 needle bar, a knocking-over comb mounted for displacement with respect to said sinker bar between said sinker bar and said needle bar, means for pulling said knocking-over comb toward said sinker bar, means for limiting the movement of 10 the knocking-over comb toward the sinker bar so as to arrest the knocking-over comb at a distance from the sinker bar, means for pulling away said knocking-over comb from said sinker bar into inactive position, and means for locking it 15 in inactive position.

2. In a flat knitting machine, a sinker bar mounted on a fixed part of the machine, a needle bar, a rocker fulcrumed on the fixed part, between said sinker bar and said needle bar, a knocking-over comb on said rocker, a spring for pulling said rocker toward said sinker bar, a lug on said rocker adapted to engage the fixed part for limiting the movement of the knocking-over comb toward the sinker bar so as to arrest the knocking-over comb 20 at a distance from the sinker bar, means for pulling away said knocking-over comb from said sinker bar into inactive position, a spring which is stronger than the first-mentioned 25 spring and connects said last-mentioned means 30 to said rocker, and a pawl for locking said last-mentioned means in the position in which said knocking-over comb is inactive.
